UNITED STATES PATENT OFFICE.

CHARLES S. EVANS, OF NORFOLK, NEBRASKA.

PRINTING-PRESS.

No. 927,030.

Specification of Letters Patent.

Patented July 6, 1909.

Application filed September 8, 1908. Serial No. 452,005.

To all whom it may concern:

Be it known that I, CHARLES S. EVANS, a citizen of the United States, residing at Norfolk, in the county of Madison and State of Nebraska, have invented certain new and useful Improvements in Printing-Presses; and I do declare the following to be a full, clear, and exact description of the invention, such as will enable others skilled in the art to which it appertains to make and use the same.

My invention relates to printing presses and particularly to that type having a continuous or substantially continuous paper feed. In this type of machine the reciprocating platen construction has been found to give much better results than the rotating platen but it has been found difficult to obtain a perfect machine having a reciprocating platen and a continuous or substantially continuous paper feed. The rotary type forms are known to possess considerably more speed than the reciprocating type form while not producing such good work.

It is the object of my invention to use a rapid continuous or substantially continuous paper feed in connection with a reciprocating platen and thereby combine the rapid operation which is the feature in the rotary machines with the good work done by the reciprocating platen type.

A further object of the invention is the provision of a press of this character which is adapted to print upon both sides of the sheet simultaneously thereby obviating the necessity of a reprint as is necessary with most machines of the reciprocating platen type.

With the foregoing and other objects in view, the invention consists of certain novel features of construction, combination and arrangement of parts, as will be more fully described and particularly pointed out in the appended claims.

In the drawings, Figure 1 is a top plan view; Fig. 2 is a longitudinal vertical section on the line 2—2 of Fig. 1, Fig. 3 is a fragmentary vertical section on the line 3—3 of Fig. 1; Fig. 4 is an enlarged detail side elevation showing the printing end of the press; Fig. 5 is a detail elevation partly in section, of the inking arm's actuating plate and its associated mechanism; and Fig. 6 is a detail eleva-

tion partly in section taken at right angles to Fig. 5, showing how the plate is operated.

55

Referring more especially to the drawing, 1 represents the base of the press which is provided with vertically extending uprights 2 which support the side and end members 3 and 4 of the frame. Upon the side and end members and the vertical uprights is supported practically all of the mechanism of the press as is usual in this class of construction. From either side of the base, adjacent its forward ends, there is extended vertically arranged standards 5 slotted throughout their length at 6 to receive the pintles 7 of the upper and lower platens 8 and 9, the latter of which is adapted to act as a type form support and travels upwardly 60 toward the bed plate 10 as will be hereinafter described. The bed plate 10 supports the other type form and is rigidly connected to the standards 5 at a level with the side and end recesses 3 and 4.

75

Opposite the ends of the bed plate 10 on either side of the machine, I journal a pair of walking beams 11 to the ends of which are connected the U-shaped links 12 having their other ends journaled upon the pintles 7 of the 80 platens members 8 and 9. The lower sides of the forward ends of the walking beams are provided with depending arms 13 to which are connected the operating links or piston rods 14. At the inner ends these rods are 85 connected to the cranks 15 carried upon the shaft 16 journaled in bearings upon the rear uprights 2 and driven by a suitable pinion 17 carried upon the driving shaft 18, also journaled upon the uprights 2, and meshing with 90 a large gear 19 upon the crank shaft 16. As the cranks 15 revolve, the walking beam 11 is reciprocated and the platens 8 and 9 are moved toward and away from the bed plate 10 simultaneously.

In order to ink the type 95 forms carried by the bed plate 10 and by the movable bed plate or platen 9, I provide suitable reciprocating inking frames 20 which carry the inking rollers 21. These frames 20 are connected to a reciprocating plate 22 by 100 links 23 and 24, both of which are pivoted to the plate and connect at their inner ends with the frames 20. The plate 22 is apertured at each end and is mounted on the side members 3 of the frame and is reciprocated, 105 as will be hereinafter described.

Suitable tracks, 25 and 26, the latter having an incline 27 leading down to the lower platen 9, are adapted to receive the friction rollers 28 carried by the inking frame so as to 5 permit these parts to move freely over the platen and bed plate. At a point adjacent the rear ends of the tracks 25 and 26, I secure suitable ink fountains 29 which have the usual inking rollers 30, mounted therein to 10 pick up and feed the ink to the inking rollers 21 as is customary.

Keyed to the shaft 16 is a sprocket wheel 31 over which a driving chain 32 passes into engagement with a sprocket pinion 33 carried upon the transverse shaft 34 mounted in bearings in standards 35. At each end of this shaft 34, I attach relatively large sprocket wheels 36 which have passing there-over the driving chains 37 upon one link of 15 each is provided a transversely extending lug 38 adapted to engage the plate 22 and move the same with its accompanying links 23 and inking forms 20 forward over the bed plates 9 and 10. The chain 37 runs over the guid-ing idlers 39 and 40 and at their extremities is passed around adjustable idlers 41 carried 20 upon the transverse shaft 42 which is mounted in the vertically disposed bearings 43 carried by the side pieces.

30 The plate, 22, is provided at its ends with transverse slots, 22^a, which are interrupted or intersected by longitudinal slots, 22^b. These slots define fingers, 22^c and 22^d which are inclined in opposite directions so as to be 35 engaged as will hereinafter be described by the lugs, 38, on the chains, 37. These lugs straddle the idlers, 40 and 41, during the movement of the plate and permit the pas-sage of said plate beyond the idlers. As the 40 chains, 37, with their lugs, 38, travel over their course they pass through the apertures, 22^a in the plate 22 and as the lugs, 38, extend across these apertures they are adapted to engage the fingers, 22^c, and move the plate 45 forward until a point is reached (shown in Fig. 5) slightly beyond the shafts, 42, of the idlers, 41. The lugs, 38, then slide down over the inclined face of the fingers, 22^c, and pass through the longitudinal apertures, 22^b. 50 After being disengaged from the plate, the lugs travel around the idlers, 41, and engage on their return course the fingers, 22^d, in a similar manner to their engagement of the fingers, 22^c. The plate is then carried rear-55 wardly past the idlers, 40, where it is disen-gaged from the lugs, 38, in the manner just described. This operation reciprocates the inking frames.

Journalized in suitable bearings adjacent 60 the standards 35, I provide the paper sup-65 porting rolls 44 and 45, the former being an idler and the latter being driven by a shaft 46 frictionally held in engagement with a disk 47 upon shaft 16 and in turn engaged 65 with the beveled gear 48 upon the shaft of

the roller 45. The paper roll is indicated in dotted lines at 49 and rests upon the rollers 44 and 45 with its free end passing over the top of the press and between the upper platen 8 and the upper face of bed plate 10 70 and over the inking rollers, 21. From thence it is passed over a return roller 50 so as to pass beneath the bed plate 10 and between said bed plate and the lower platen 9. From here it passes to the feeding rollers 51 and 75 52, the former of which is carried upon a movable link 53 having one end pivotally and slidably connected with a pin 54 extending outwardly from the bearing 55. The op-posite end of the link 53 is connected to one 80 arm of a bell crank lever 56 journaled in bearings upon the frame and controlled by a reciprocating rod 57 which is engaged by the knob 58 carried upon an arm depending from the plate 22, as shown in Fig. 2 so that 85 the roller 51 is raised from its companion idler 52 at each stroke of the inking forms. This release mechanism is duplicated on the opposite side of the frame and the shafts which support the rolls 52 and 53 and also 90 the bell crank lever 56 are passed across the machine as shown in Fig. 1 to the duplicate mechanism on the opposite side. When the roller 51 is raised from its companion 52 the paper feed is stopped sufficiently long enough 95 for the platens to engage the bed plate and make the proper impression. The roller 51 is provided with a suitable sprocket wheel 57 which is operated by the chain 58 coming from the folder mechanism driving shaft to 100 which is secured the driving pinion 59 con-nected by sprocket chains 60 and 61 with the sprocket wheel 62 carried upon the shaft 16. The paper passes from the feeding rollers 51 and 52 to the usual folder which may be 105 driven directly from the shaft 16 as shown or may be independently driven as may be found expedient.

From the foregoing description taken in connection with the accompanying drawings, 110 the construction and operation of the invention will be readily understood without re-quiring a more extended explanation.

Various changes in the form, proportion and the minor details of construction may be 115 resorted to without departing from the prin-ciple or sacrificing any of the advantages of the invention, as defined in the appended claims.

I claim as my invention:—

1. In a printing press, a pair of bed plates, platens for coöperating therewith, a source of paper supply, means to feed the same to the bed plates, inking mechanism means for oper-ating the same, a tripping mechanism for 125 controlling the paper feed, and means carried by the inking mechanism for operating the tripping mechanism.

2. In a printing press, a pair of bed plates, platens for coöperating therewith, a source of 130

paper supply, means to support the same on the press, inking mechanism, means for operating the same, a pair of rollers arranged in the paper feed, a tripping mechanism for raising one of said rollers and a stud carried by the inking mechanism for operating said tripping mechanism.

In testimony whereof I hereunto set my hand in presence of two subscribing witnesses.

CHARLES S. EVANS.
